UNITED STATES PATENT OFFICE.

CHARLES FRANCIS JENKINS, OF WASHINGTON, DISTRICT OF COLUMBIA, ASSIGNEE TO
DISCROLA, INC., OF WASHINGTON, DISTRICT OF COLUMBIA, A CORPORATION.

MOTION-PICTURE CARRIER.

1,409,004.

Specification of Letters Patent.

Patented Mar. 7, 1922.

Application filed April 14, 1921. Serial No. 461,428.

To all whom it may concern:

Be it known that I, CHARLES FRANCIS JENKINS, a citizen of the United States, and resident of Washington, in the District of Columbia, have invented certain new and useful Improvements in Motion-Picture Carriers, of which the following is a specification, reference being had therein to the accompanying drawing.

10 This invention relates to carriers for motion pictures, the pictures being borne upon the marginal portion of a plurality of equal superposed disks which may be of paper. The general object of the invention is to secure at extremely low cost a compact, convenient and durable device for carrying a great number of pictures in such a way that they may be conveniently displayed by devices not herein set forth.

20 The superposed disks usually form a thick tablet bearing pictures which are all in the usual sequence and suitable central means are employed to bind the disks together firmly and prevent their relative rotation.

25 In the accompanying drawings, which are diagrammatic,

Figure 1 shows the broad upper face of a tablet, the picture spaces thereon being indicated only in part.

30 Figure 2 shows the edges of some of the disks, which are shown as spaced apart to make clear their relative positions.

35 In these views, A represents the upper disk of the series, each disk of which bears near its edge 5 closely adjacent pictures 6 arranged in circular series, and all the disks are secured together by a central tubular rivet 7. Each disk has at some distance from both its center and its margin a preferably circular aperture 8 and these apertures are primarily in registry. All the registering punched disks are cut along a line 9 extending from the apertures 8 to the edge 5. The disks are then progressively offset or turned 40 angularly in the same direction through angles each equal to the angle at the center subtended by one or more of the marginal picture spaces. When thus adjusted the disks are locked against relative rotation by a second eyelet 10 inserted at a little distance from the center.

45 In Figure 1, the marginal portion A' of the upper disk A is visible, but the opposite marginal portion A'' is placed under the 50 marginal portion B' of the second disk B,

and marginal portion B'' of the disk B is placed under the marginal portion C' of the disk C, and so on for all the disks. It follows that the marginal portions of the disks form in effect a continuous picture bearing spiral which is most conveniently and inexpensively formed of primarily independent superposed disks connected as set forth. If beginning at the line 9 the marginal portion of the disk A is progressively raised in passing around its circumference, the portion B' of the second disk which corresponds to the portion A' of the first disk, will be raised, and by continuing the process all the pictures on all the disks will be exposed in succession.

55 The somewhat large periphery of the aperture 8 makes tearing at the inner end of the line 9, in raising the margins of the disks, very unlikely, and practically no difficulty is met in this respect.

60 The number of disks is as great as may be desired, and they are usually printed with the pictures of all in proper sequence. When many like disks of each kind have been 65 printed, they are arranged in sets, adjusted, and secured together in the manner already set forth.

65 The cost of a set of pictures corresponding to those usually upon a single film or "reel" of the ordinary kind is relatively extremely insignificant, and it is quite possible to form, adjust and use the tablets by very simple appliances.

70 What I claim is.

75 1. As a motion picture carrier, a practically continuous spiral made up of the marginal portions of approximately plane superposed registering disks fixed to each other centrally and each bearing marginally a series of motion pictures.

80 2. In a motion picture carrier, a series of approximately plane superposed disks bearing marginal pictures and each marginally engaging at one point the next disk below 85 in such manner as to form with said next disk a practically continuous spiral.

85 3. As a motion picture carrier, a series of distinct superposed thin elastic disks all cut inwardly from their periphery and angularly offset progressively, about a common axis, with respect to the succeeding disks respectively, and all secured against further offsetting.

90 4. A series of distinct superposed disks,

90

95

100

105

110

bearing marginal motion pictures, centrally secured together, cut inwardly from their margins, respectively, progressively offset angularly, and each having one margin,
5 formed by such cutting, inserted beneath a margin formed by the cutting of the succeeding disk.

5. A series of distinct superposed disks centrally secured together, bearing marginal
10 series pictures, each having an opening at

some distance from both center and margin and a cut extending from each opening to the corresponding margin, the cuts being angularly offset through an angle at the center subtended by one or more pictures,¹⁵ and all the disks being secured against relative angular displacement.

In testimony whereof I hereunto affix my signature.

CHARLES FRANCIS JENKINS.
